UNITED STATES PATENT OFFICE.

CHARLES F. LEMBKE, OF VALPARAISO, INDIANA.

INTERNAL-COMBUSTION ENGINE.

1,076,380.

Specification of Letters Patent.

Patented Oct. 21, 1913.

Application filed February 6, 1912. Serial No. 675,705.

To all whom it may concern:

Be it known that I, CHARLES F. LEMBKE, a citizen of the United States, residing at Valparaiso, in the county of Porter and State 5 of Indiana, have invented new and useful Improvements in Internal-Combustion Engines, of which the following is a specification.

This invention relates to the general structure of an internal combustion engine and more particularly to the valve mechanism and the actuating means therefor and to the means for controlling the inlet of the fluid medium and the exhaust of the burned 15 gases.

The invention further contemplates a single valve for each cylinder for controlling the admission of the gaseous mixture and the escape of the products of combustion, 20 said valve automatically taking up wear and being counterbalanced to a certain degree so as to prevent lateral thrust, particularly during combustion of the explosive mixture.

25 The invention consists of the novel features, details of construction and combination of parts, which hereinafter will be more particularly set forth, illustrated in the accompanying drawing, and pointed out in 30 the appended claim.

Referring to the drawings, forming a part of the specification, Figure 1 is a section of an internal combustion engine embodying the invention. Fig. 2 is a view in elevation 35 of one of the piston valves. Fig. 3 is a section of the valve on the line y—y of Fig. 2. Fig. 4 is a sectional view of the cam shaft. Fig. 5 is a front view of a portion of the cam shaft, showing the cam in position 40 thereon and the bell crank coöperating therewith.

Corresponding and like parts are referred to in the following description, and indicated in all the views of the drawings, by the 45 same reference characters.

The crank shaft I is mounted in bearings of a suitable framework, which in the present instance consists of a crank case 2, the latter having a sump 3 for receiving a quantity 50 of oil which is applied to the moving parts by a splashing action. The cam shaft G is arranged parallel with the crank shaft I and is mounted in suitable bearings arranged within the crank case. The cam shaft G is driven from the crank shaft, the latter making two revolutions to each revolu-

tion of the cam shaft in the usual manner. The cam H rotatable with the cam shaft consists of a disk having portions deflected to form the cam whereby the valve is properly operated. It is noted in this connection that no spring is required, since the valve is moved positively in each direction by means of the cam. The cylinder E is bolted or otherwise secured to the crank case and is provided with a jacket C forming a space through which the cooling medium, such as water, is circulated. The valve chamber is indicated at 6 and is located at one side of the cylinder and preferably forms a part 60 thereof. The valve chamber 6 is of cylindrical form and is jacketed so as to be cooled by means of the water circulating through the space C. The water enters the space C at U and leaves said space at A. The exhaust manifold B has connection with the upper end of the valve chamber 6. The intake manifold T has connection with the valve chamber 6 at a point intermediate of its ends. The inlet port establishing communication between the manifold T and the valve chamber is indicated at M. The cylinder E has a port O near its upper end which establishes communication with the valve chamber. The gaseous mixture enters by way of the port O and the burned gases leave by way of the same opening. A piston F is arranged to operate in the cylinder E and has connection with the crank portion of the crank shaft by means of a 70 pitman P. The spark plug is indicated at R and is located at the upper end of the cylinder.

A valve D is had for the valve chamber and consists of a piston arranged to reciprocate therein, said valve being hollow and having ports L and N, the port L being adapted to register with the inlet port M and the port N being adapted to register with the port O. An annular channel 7 is 75 formed in the upper portion of the piston valve and is adapted to register with the port O during compression, explosion and expansion of the gaseous mixture so as to practically equalize the pressure on the sides 80 of the valve so that the same may be moved by the expenditure of a comparatively small amount of force and with a minimum amount of friction. The upper portion of the valve has packing rings, the same being located above and below or on opposite sides of the annular channel 7, thereby con-

tinuing the pressure. By having the valve provided with packing rings such as commonly employed in explosive engines the necessity for grinding valves is wholly obviated and any wear between the valve and its casing is automatically taken up by the expansion of the packing rings. A bell crank J is mounted upon a lug K and one arm is connected by means of a link Y with the valve to be operated. The other arm of the bell crank is bifurcated, each bifurcation being provided with a roller or small wheel 8. The bifurcations of the bell crank extend upon opposite sides of the cam disk H, with the result that the bell crank is positively rocked in each direction by means of the cam disk, thereby moving the valve in both directions and obviating the use of any springs. The parts are so arranged that when the piston is upon its outstroke, after being driven inwardly by the expansion of the gases due to explosion, the valve occupies a position wholly below the port O so that the burned gases may pass freely from the cylinder into the upper portion of the valve chamber or casing 6, thence into the exhaust manifold B. When the piston is on the instroke to draw in a charge the valve is moved to a position to bring the port N thereof in register with the port O and when the piston is on the compressing stroke and on the working stroke, being driven by the expansion of the gases due to combustion, the valve is moved to bring the annular space 7 in register with the port O for the purpose herein stated. The interior of the valve is at all times in communication with the intake manifold and the valve is partly cooled by the surrounding space C through which the water is circulated and by the gaseous mixture which is drawn through the valve.

The invention simplifies the general structure of engines of the internal combustion type and enables the parts to be materially reduced in number and conserves power, since no springs are required to operate in conjunction with the valves and it is not necessary to grind the valves as is essential in the operation of explosive engines

embodiment valves of the poppet type. The crank case, in which is located the bearings of the cam and crank shafts, also receives the cylinder and valve chamber and access is readily had thereto by means of a plate 55 S which is made removable and the crank case itself is composed of sections which are bolted together, thereby admitting of the parts being readily passed and machined so as to be properly fitted to prevent leaky 60 joints.

From the foregoing description, taken in connection with the accompanying drawings, the advantages of the construction and of the method of operation will be readily 65 apparent to those skilled in the art to which the invention appertains, and while I have described the principle of operation of the invention, together with the device which I now consider to be the best embodiment 70 thereof, I desire to have it understood that the device shown is merely illustrative, and that such changes may be made when desired as are within the scope of the claim appended hereto. 75

Having thus described the invention what is claimed as new, is:

In an internal combustion engine, the combination of a cylinder having a port, a valve chamber at one side of the cylinder and in 80 communication therewith through said port, said valve chamber having its outer end in communication with the exhaust and having an intake intermediate of its ends, and a piston valve arranged to operate in the valve 85 chamber and having an interior space and provided in its sides with openings to register with the intake and with the said cylinder port, said valve further having an annular channel near its outer end to register 90 with the cylinder port and said valve further having packing rings upon opposite sides of the annular channel.

In testimony whereof I affix my signature in presence of witnesses.

CHARLES F. LEMBKE.
